United States Patent Office

Des. 180,913
Patented Sept. 3, 1957

180,913

SKI POLE HANDLE

John D. Mossop, Toronto, Ontario, Canada, assignor to
The Allcock, Laight & Westwood Company of Toronto
Limited, Leaside, Toronto, Ontario, Canada
Application November 1, 1956, Serial No. 43,640

Claims priority, application Canada July 7, 1956

Term of patent 14 years

(Cl. D34—14)

The single figure is a perspective view of a ski pole handle, showing my new design.

The opposite side not shown, has substantially the same appearance as the side shown.

I claim:

The ornamental design for a ski pole handle, as shown and described.
